UNITED STATES PATENT OFFICE.

FRANKLIN K. YOUNG, OF WINTHROP HIGHLANDS, MASSACHUSETTS.

FIREARM.

1,200,685.

Specification of Letters Patent. Patented Oct. 10, 1916.

Application filed December 22, 1913. Serial No. 808,053.

To all whom it may concern:

Be it known that I, FRANKLIN K. YOUNG, a citizen of the United States, residing at Winthrop Highlands, county of Suffolk, 5 State of Massachusetts, have invented an Improvement in Firearms, of which the following description, in connection with the accompanying drawing, is a specification, like characters on the drawing representing like parts.

This invention relates to firearms of the type in which the explosion of the cartridge automatically causes the extraction and ejection of the spent cartridge case, the resetting 15 of the firing mechanism and the insertion of a fresh cartridge and has for an object to provide an improved arm of simple and cheap construction which may be used either as a semi-automatic or as a full-automatic 20 arm.

Another object is to provide an arm of this type having a simple firing mechanism consisting of few parts and one which will be certain and reliable in operation.

This invention provides a convertible 25 automatic arm having few parts in which the firing pin is automatically operated without the provision of a hammer operating thereagainst.

The nature and objects of the invention 30 will more fully appear from the following specification and accompanying drawings and the novel features will be particularly pointed out in the claims.

Referring to the drawings in which I have 35 illustrated a pistol constructed in accordance with my invention; Figure 1 is a sectional view showing the arm loaded and ready for firing, the parts being shown in 40 position to operate as a semi-automatic arm; Fig. 2 is a sectional view on the line 2—2, Fig. 1; Fig. 3 is a sectional view similar to Fig. 1 showing the breech block in its rear or retracted position, parts of the frame being broken away; Fig. 4 is a sectional view 45 on the line 4—4, Fig. 1; Fig. 5 is a sectional view on the line 5—5, Fig. 1; Fig. 6 is a sectional view on the line 6—6, Fig. 1; Fig. 7 is a detail view of the ejector cam, and Fig. 50 8 is a detail view of the adjustable trigger.

Referring to the drawings in detail 1 designates the frame having a grip 2 and a barrel 3. The grip is chambered to receive the magazine 4, of usual construction, the grip 55 being made long enough to receive a magazine of the size desired. The barrel is bored

and rifled in the usual manner as indicated at 5 and is also bored as indicated at 6 to provide a recoil spring chamber. A breech block 7 is mounted on the frame to move toward and from closed or firing position and in the construction illustrated is mounted to slide longitudinally behind the barrel, being provided at its sides with downwardly projecting flanges 8 which have tongue and groove connection with the frame, as indicated at 9. The breech block is provided with a bolt 10 extending through a hole 11 into the recoil spring chamber. A recoil spring 12 surrounds the bolt thus yieldably urging the breech block forward and its tension may be adjusted by means of a nut 13 on the threaded end of the bolt 10. The end of the recoil spring chamber is preferably closed as by means of a screw plug 14. The rear end of the barrel is shaped to provide a firing chamber to receive the cartridge as indicated at 15. The magazine 4 of usual construction, is adapted to project fresh cartridges successively into position to be 80 engaged by the breech block and carried forward thereby into the firing chamber as the breech block moves forward after recoil.

The firing pin 16 is slidably mounted in the breech block in position to engage the priming cap of the cartridge located in the firing chamber and is urged forward by a spring 17 compressed between a shoulder 18 on the firing pin and a U-shaped plate 19 which fits in a transverse groove in the breech block and is held in place by a set screw 20. The weight of the firing pin and the strength of the spring are so proportioned that if the firing pin is drawn back, compressing the spring, and then released 95 the cartridge will be exploded. By this construction it is unnecessary to provide a hammer to operate in connection with the firing pin. The firing pin illustrated is made in three parts secured together. The central part 21 is in the form of a block having two downwardly presented shoulders 22 and 23 to be engaged by the sear 24 and cocking pawl 25 respectively. The forward part is of such shape that it may be conveniently turned in a lathe and presents a reduced forward end 26 which extends through a hole in the forward end of the breech block into operating position. The rear portion 27 is in the form of a knurled screw bolt projecting to the rear of the breech block in a recess 28 to provide con-

venient means for cocking the firing pin by hand.

The sear 24 is pivoted at 29 in the frame and is provided with a downwardly extending arm to which a link 30 is connected. This link moves in ways in the frame and is shaped to fit around the magazine so as not to interfere therewith as indicated in Fig. 2. A spring 31 conveniently mounted presses this link rearwardly thus urging the sear into position to engage the shoulder 22 of the firing pin. During the forward movement of the breech block the sear is pressed against the under surface 32 of the breech block in position to engage the shoulder 22 when the breech block has moved forward sufficiently. This shoulder 22 extends somewhat below the plane of the surface 32 to insure its engagement with the sear. A spring-pressed pawl 33 is pivoted to the link near its forward end and projects downwardly for engagement with the trigger 34. The frame is milled out as indicated at 35 to provide space for the trigger and allied parts, the plate 36 being pinned in the slot to close the opening thus formed.

The connection between the trigger and the link is made adjustable so that the operation of the link by the trigger may be varied to provide for semi-automatic and full-automatic operation of the arm, a further variation providing a safe position of the parts. As a convenient method of providing this variable connection, I make the trigger of adjustable length and in the form illustrated, the trigger is pivoted in the frame and is provided with an adjustable thumb plate 37 secured thereto by screws 38 extending through slots in the plate and secured in the trigger. I prefer to provide means to hold the plate in adjusted position and this may conveniently be done by providing a flexible detent 39 which may engage either of the notches 40, 41 or 42 in the trigger to hold the plate respectively in safe position, position for full-automatic operation and for semi-automatic operation. The end of the flexible detent extends through a slot in the side of the frame whereby the plate may be moved to the several positions. When in its lowest or safe position with the detent in the notch 40, the trigger is too short to engage the pawl 33. When the plate is so positioned its lowest end projects below the edge of the trigger guard in such manner that its position will be readily noticed either upon looking at the arm or upon inserting the finger into the trigger guard, thus avoiding the mistake of trying to shoot without first moving the plate from safe position. When this plate is in mid-position, it is adapted to engage the pawl as the trigger is operated and thereby withdraw the sear from the shoulder, the with-

drawal, however, is only momentary, for upon further movement, the trigger slips from the pawl and the sear returns to position to engage the shoulder 22 and hold the firing pin retracted. To fire another shot the trigger must be released and again pulled. When the plate is in its uppermost position, the plate will continue to engage the pawl during the full movement of the trigger thus holding the link 30 in its forward position and the sear retracted so long as the trigger is held back by the finger. Accordingly full automatic operation results.

It is necessary to provide means for cocking the firing pin automatically when the arm is used as a full-automatic arm. I prefer to provide means independent of the sear such as a pawl to engage the firing pin during the forward movement of the breech block and hold said firing pin against forward movement until the breech block reaches substantially its forward position at which time the pin is released. Accordingly the frame is slotted as indicated at 43 and the spring-pressed pawl 25 is pivoted therein. The movement of the pawl is limited by a pin 44 secured in the frame and projecting into a slot 45 in the pawl. This pawl is pressed upwardly by a spring 46 mounted in a block 47 secured in the slot 43. Upon return movement of the breech block after discharge under the action of the recoil spring 12, the pawl engages the shoulder 23 on the block of the firing pin and thus holds the firing pin while the breech block continues its forward movement. As the breech block approaches its closed position, however, the shoulder 48 thereof engages the inclined face 49 of the pawl and presses it downward against the operation of its spring thus withdrawing the pawl from the firing pin and allowing the firing pin to move forward under the operation of its spring to explode the cartridge which by this time is pushed forward into the firing chamber.

Any suitable extracting and ejecting mechanism may be provided. For the purpose of illustration, I have shown one form of such mechanism, in which an extracting claw 50 is secured in a slot 51 in the side of the breech block. This claw is positioned to engage the spent cartridge case and withdraw it from the firing chamber as the breech block moves back after discharge. An ejector 52 is arranged to engage the lower edge of the spent cartridge case as the breech block moves back far enough to withdraw the spent case from the firing chamber. This ejector is illustrated as a bell crank lever the ejecting arm of which is positioned in the central plane of the breech block and is arranged to move upwardly in a slot 53 in the breech block provided there-

for. The other arm is positioned at one side of the breech block and is provided with a projection 54 operating in a cam slot in the hardened steel cam 55 secured in the side 5 of the breech block.

The operation of the arm when used as a semi-automatic arm is as follows:—With the magazine full and a cartridge in the firing chamber, the parts being in the position shown in Fig. 1, the trigger is pulled, the upper end of the plate 37 engages the pawl 33 drawing the link 30 forward against the operation of its spring. The sear 24 is thus retracted from the shoulder 22 of the firing pin block and at substantially the same time the end of the plate 37 slips off from the pawl 33 allowing the link and sear to return to normal position. The cartridge is exploded by the forward 15 movement of the firing pin under the influence of the spring. The explosion of the cartridge causes the recoil of the breech block thus actuating the extracting, reloading and firing mechanism. The spent cartridge case is withdrawn from the firing chamber by the extractor claw 50 and the ejector 52 controlled by the cam 55 is moved forwardly into engagement with the lower edge of the cartridge case thus ejecting the 20 spent case. A fresh cartridge is pressed upwardly to the top of the magazine and into position to be carried forward by the return movement of the breech box. Upon the forward movement of the breech block under 25 the action of the recoil spring, the fresh cartridge is carried forward into the firing chamber. The cocking pawl 25 engages the firing pin block 21 thus cocking the firing pin as the breech block moves forward and 30 as the breech block reaches its extreme forward position the shoulder 48 engages the cocking pawl retracting it from the shoulder 23 of the firing pin block. The sear 24 will, however, engage the shoulder 22 of 35 the firing pin block and prevent the firing pin from moving forward to explode the cartridge. The trigger is then released and as the thumb plate 37 moves back, the pawl yields swinging backwardly upon its pivot 40 until the plate passes behind the pawl when it again springs forward into position and the arm is ready to be discharged again by the movement of the trigger.

It may be noted that the automatic cocking mechanism is superfluous when the arm is used as a semi-automatic arm since the sear would operate to cock the firing pin. The cocking pawl illustrated, however, does not interfere with the operation of other 50 parts and for this reason I prefer not to provide means for making this automatic cocking and releasing mechanism inoperative when the arm is used as a semi-automatic arm.

65 The arm may be converted into a full-

automatic arm by moving the thumb plate 37 upward. The operation is then substantially the same except that when the trigger is pulled the plate continues to engage the pawl 33 holding the link in forward position and the sear retracted. The firing pin will then operate automatically to discharge the cartridge in the firing chamber as soon as released by the action of the breech block against the cocking pawl.

I have described one embodiment of my invention for the purpose of illustration. It is obvious, however, that various changes in structure may be made within the scope of my invention.

Having fully described my invention, what I claim as new and desire to secure by Letters Patent is:

1. In a firearm, a sear and sear operating means comprising a link connected to the sear, a trigger having a movable thumb plate thereon adapted when in its uppermost position to engage the link thereby providing a connection between the trigger and link and when in its lowermost position to be entirely free from said link, the thumb plate having a projection by which it may conveniently be adjusted.

2. In a firearm, a frame comprising a barrel, a magazine carried in the frame, a slidable breech block, a recoil spring yieldably urging the breech block toward the barrel, a spring-pressed firing pin slidably mounted in the breech block and provided with a shoulder, a sear engaging said shoulder, operating means for said sear variable to withdraw the sear from the firing pin and hold it withdrawn or to withdraw it momentarily and release it and means to engage the firing pin and temporarily hold it against forward movement during a portion of the forward movement of the breech block.

3. In a firearm, a frame comprising a barrel, a magazine carried in the frame, a slidable breech block, a recoil spring yieldably urging the breech block toward the barrel, a spring pressed firing pin slidably mounted in the breech block and provided with a shoulder, a sear engaging said shoulder, operating means for said sear to release it from engagement with the shoulder of the firing pin and a spring-pressed pawl pivoted in the frame normally positioned to engage the firing pin during the forward movement of the breech block, the breech block having a shoulder to engage and release the pawl from the firing pin as the breech block approaches its forward position.

4. In a firearm, a frame comprising a barrel, a magazine carried in the frame, a slidable breech block, a recoil spring yieldably urging the breech block toward the barrel, a spring-pressed firing pin slidably

- mounted in the breech block and provided with a shoulder, a sear engaging said shoulder, operating means for said sear to release it from engagement with the shoulder 5 of the firing pin and a spring-pressed pawl pivoted adjacent the rear of the frame having a limited movement and positioned to engage the firing pin during the forward movement of the breech block and having 10 a cam surface, said breech block having a shoulder positioned to engage the cam surface of the pawl to release said pawl from the firing pin as the breech block approaches its forward position.
- 15 5. In a firearm, a frame comprising a barrel, a magazine carried in the frame, a slideable breech block, a recoil spring yieldably urging the breech block toward the barrel, a spring-pressed firing pin slidably mounted 20 in the breech block and provided with a shoulder, a sear engaging said shoulder, sear operating means comprising a link connected to the sear and a trigger of variable length whereby the trigger may be adjusted 25 to draw the link forward temporarily and release it or to draw it forward and hold it, and means to automatically cock the firing pin.
6. In a firearm, a frame comprising a barrel, a magazine carried in the frame, a slideable breech block, a recoil spring yieldably urging the breech block toward the barrel, a spring-pressed firing pin slidably mounted 30 in the breech block and provided with a shoulder, a sear engaging said shoulder, sear operating means comprising a trigger having an adjustable thumb plate whereby the connection between the sear and trigger may be varied to cause the operation of the trigger 35 to retract the sear momentarily and release it or to retract the sear and hold it retracted, and means to automatically cock the firing pin.
7. In a firearm, a frame comprising a barrel, a magazine carried in the frame, a slideable breech block, a recoil spring yieldably urging the breech block toward the barrel, a spring-pressed firing pin slidably mounted 40 in the breech block and provided with a shoulder, a sear engaging said shoulder, sear operating means comprising a link having a trigger-engaging projection, and a trigger of variable length whereby the operation of the trigger will cause the sear to be retracted 45 and released or will cause the sear to be retracted and held retracted as the length of the trigger is made respectively short or long and means independent of the sear to automatically cock the firing pin during the 50 movement of the breech block.
8. In a firearm, a frame comprising a barrel, a magazine carried in the frame, a slideable breech block, a recoil spring yieldably urging the breech block toward the barrel, a spring-pressed firing pin slidably mounted

in the breech block and provided with a shoulder, a sear engaging said shoulder, sear operating means comprising a trigger having an adjustable thumb plate to vary the effective length of said trigger, a link connected to the sear and having a spring-pressed pawl projecting into the path of the thumb plate the plate being adjustable to three positions on the body of the trigger in which positions respectively the plate will be 70 inoperative, will engage the pawl momentarily and release it and will engage the pawl to retract the sear and hold it retracted, and means independent of the sear to automatically cock the firing pin.

9. In a firearm, a frame comprising a barrel, a magazine carried in the frame, a slideable breech block, a recoil spring yieldably urging the breech block toward the barrel, a spring-pressed firing pin slidably mounted 85 in the breech block and provided with a shoulder, a sear engaging said shoulder, a trigger, operative connections between the trigger and sear, means to vary the engagement between the trigger and sear connections whereby the trigger may operate to withdraw the sear and hold it withdrawn or to withdraw the sear momentarily and release it and separate means to cock the firing pin automatically.

10. In a firearm, a frame, a barrel, a breech block slideable upon said frame, a spring-pressed firing pin slideable within said breech-block and provided with a shoulder, a spring-pressed pawl pivoted in said frame to engage said shoulder of said firing pin and hold said firing pin retracted until said breech block on its forward movement engages and depresses said pawl to release said firing pin and a recoil spring to yieldingly urge said breech block on its extreme forward movement into contact with said barrel.

11. In a firearm, the combination of a movable breech block, a spring-pressed firing pin slideable therein, a spring-pressed pawl adapted to engage and to hold retracted the firing pin during a portion of the forward movement of the breech block, a shoulder on said breech block adapted to engage and depress said pawl at a subsequent portion of the forward movement of the breech block whereby the release of the firing pin is effected after a predetermined interval.

12. In a firearm, the combination of a movable breech block, a spring-pressed firing pin slideable therein, a spring-pressed pawl adapted to engage and to hold retracted the firing pin during a portion of the forward movement of the breech block, 120 a shoulder on said breech block, said pawl having a surface presented to the path of said shoulder whereby the release of the firing pin is effected upon further forward movement of the breech block.

13. In a firearm, the combination of a frame, a movable breech block thereon, a spring-pressed firing pin slidable in said block, the frame having a recess in the rear thereof, a spring-pressed pawl mounted in said recess and adapted to engage and to hold retracted the firing pin during a portion of the forward movement of the breech block, a shoulder on the end of the breech block adapted to engage and depress said pawl upon subsequent forward movement of the breech block toward closed position, whereby release of the firing pin is effected.

In testimony whereof, I have signed my name to this specification, in the presence of two subscribing witnesses.

FRANKLIN K. YOUNG.
